[57] CLAIM

The ornamental design for a disk storage case, as shown and described.

DESCRIPTION

FIG. 1 is a perspective view of a disk storage case showing my new design;

FIG. 2 is a perspective view with one drawer in open condition;

FIG. 3 is a left side elevational view of FIG. 1, the right side being a mirror image thereof;

FIG. 4 is a front elevational view thereof;

FIG. 5 is a rear elevational view thereof;

FIG. 6 is a bottom plan view thereof;

FIG. 7 is a top plan view thereof;

FIG. 8 is a perspective view of a second embodiment of the disk storage case shown in FIG. 1;

FIG. 9 is a perspective view with the drawers in open condition;

FIG. 10 is a left side elevational view of FIG. 8, the right side being a mirror image thereof;

FIG. 11 is a front elevational view thereof;

FIG. 12 is a rear elevational view thereof;

FIG. 13 is a bottom plan view thereof; and

FIG. 14 is a top plan view thereof.
